CLAIM

The ornamental design for a handset, as shown and described.

DESCRIPTION

FIG. 1 is a perspective front view of a handset showing our new design;

FIG. 2 is a perspective rear view thereof;

FIG. 3 is a front view thereof;

FIG. 4 is rear view thereof;

FIG. 5 is a left side view thereof;

FIG. 6 is a right side view thereof;

FIG. 7 is a top view thereof; and,

FIG. 8 is a bottom view thereof.

The broken line showing of the environment of the handset in FIGS. 1-8 is for illustrative purposes only and forms no part of the claimed design. The unshaded regions within the bounds of the broken lines form not part of the claimed design.

1 Claim, 6 Drawing Sheets
